SAFETY MANHOLE COVER LOCK

Charles B. Wiegel, Chicago, Ill.

Application June 6, 1950, Serial No. 166,405

11 Claims. (Cl. 70—168)

This invention relates to improvements in manhole covers, an object being to provide a safety manhole cover largely to prevent accidents to children, whose curiosity, whetted perhaps by admonitions to the contrary, leads them to pry up and remove ordinary manhole covers to disclose the mysteries beneath, with the result that they are apt to fall in and be injured or drowned.

The unauthorized opening of such manholes is not confined to children, however. They are at times used for the surreptitious disposal of trash or articles, and sometimes for the concealment and disappearance of evidence of crime.

Accordingly, it is an object of the invention to provide a safety manhole cover which, when once satisfactorily secured in place, cannot be removed by pries or ordinary tools applied or inserted around the edge of the cover or otherwise, but can only be lifted or removed from the manhole rim or ring or opening by first unlocking the same, as by a special key.

Other objects are to provide such a safety manhole cover in which the key cannot be removed therefrom without placing the mechanism in locking position, which tends to prevent overlooking the locking of the cover when it is applied to the manhole and the positioning of the cover in the manhole opening in the absence of the key in the cover. The key may also form a convenient handle to assist in handling and manipulating the cover in applying and removing the same.

Other objects of the invention are to provide such a safety manhole cover which is adapted for use with manholes of standard type and which is sturdy and strong, simple in construction and operation, and relatively inexpensive.

Further objects and advantages will appear from the description and claims to follow, in connection with the accompanying drawing which illustrates, by way of example but not of limitation, an embodiment of the invention, and in which drawing:

Figure 1 is a vertical section through a typical manhole with the cover in place thereon, said section being taken on the line 1—1 of Fig. 2;

Fig. 2 is a view taken on the plane indicated by the line 2—2 in Fig. 1 and looking upwardly to show the bottom of the cover in relation to the manhole;

Fig. 3 is a vertical section on the line 3—3 of Fig. 2, through the cover-holding and locking mechanism, the parts being shown right side up;

Fig. 4 is a plan view of the locking keyhole in the cover taken on the line 4—4 of Fig. 3;

Fig. 5 is a horizontal section on the line 5—5 of Fig. 3 and showing the position of the key in the unlocked position of the cover-locking means;

Fig. 6 is a perspective view of the bracket on the underside of the cover plate for supporting the locking mechanism; and

Fig. 7 is a perspective detail view of one of the other locking brackets.

Referring to these views, particularly Figs. 1 and 2, the usual manhole for catch basins, drain pits and sewer connections comprises a relatively large circular opening 10 in a concrete slab 11 which is laid and secured on top of the brick wall 12 lining the hole in the ground 13 and leading to the catch basin or the like below. The wall is larger in diameter than the said opening and the inwardly projecting portion of the slab around the opening forms the ledge of the manhole. The concrete slab may extend

outwardly as far as desired, and its upper surface is usually substantially at the surrounding ground level.

The opening 10 is surrounded by a depression or recess 15 to receive the peripheral edge of a circular cover plate 16, the upper surface of which, when the cover is in position to cover the opening, may be substantially flush with the top of the concrete slab. A metal ring is sometimes embedded in the concrete to form the edge of the opening 10, but this cover is applicable thereto in the same manner as herein shown and described.

The cover 16 may be of the usual cast-metal type having preferably a roughened upper surface and such legends as may be desired thereon, and is of considerable weight. An annular raised rib 19 may be formed on the lower side to assist in centering the cover in the manhole opening. The edge of the cover fits freely into the annular depression 15 of the manhole ledge.

In order to prevent removal of the cover from its position when in place on the manhole by prying under its edge or the like, a plurality of holders or clamps are provided on the underside of the cover which engage under the manhole ring and lock it in place.

Two, preferably, of these locking holders 20, 20, as seen in Fig. 2, are located on one side of the center of the cover and another, 21, on the other side of the center. The holders 20 are fixed, but the holder 21, or the manhole ledge gripping part thereof, may be withdrawn from its ledge-engaging position, as later explained, by a suitable key operated from the top side of the cover.

Each of the holders or clamps 20 comprises a metal bracket 22, the foot of which is secured, as by screw bolts 23, to the underside of the cover and an angle member 24 bolted to the bracket 22 by bolts extending through an adjusting slot, or slots, 25 therein, Fig. 7, and having a leg 26 extending under and engaging the lower edge of the manhole ledge. The object of the fixed adjustment in this bracket combination is to accommodate the holders to ledges having varying thicknesses.

The holders or clamps 20 are spaced apart circumferentially of the cover to give spaced locking points with the manhole ledge for greater strength and for greater resistance to prying-up efforts at the sides, and to assist in applying the cover to the manhole opening.

The combined angular or Z bracket 22, 24, 26 is thus comparatively strong and rigid to prevent raising the cover at the edge, yet with sufficient resiliency to permit the arms or legs 26 with their slightly down-turned ends to give sufficiently to permit the cover to be slid or turned into its position in the manhole; and conversely, when withdrawing the cover, by the reverse movements the arms 26 will give sufficiently to enable the cover to be tipped up and withdrawn.

The clamp or holder 21 opposite the clamps 20, which may be withdrawn from engagement with the manhole ledge for the placement and removal of the cover and shown in an enlarged scale in Figs. 3 to 6, comprises a depending bracket 30, Fig. 6, bolted as shown or otherwise secured to the underside of the cover. A horizontal member 31 is punched and bent from the vertical portion of the bracket 30 and its lower end is bent into another suitably positioned horizontal supporting member 32. A horizontal slot 33 and vertical communicating slot or notch 34 are formed in bracket 30. Aligned holes are formed in the two members 31 and 32, which in turn vertically align with the circular portion of the keyhole 35 formed in the cover plate 16.

This locking clamp or holder 21 includes a vertically movable stem or shaft 36 passing up through the apertures in the members 32 and 31 of the bracket 30 and into the keyhole 35 in the cover, terminating at its upper end substantially flush with the upper surface of the cover 16 when in its uppermost position. At its lower end the stem 36 has rigidly secured thereto, as by rivetting or otherwise, the horizontal locking, clamping or holding member 37, corresponding to arms 26 of the clamps 20 in the sense that it is adapted to engage under the manhole ledge to hold the cover in its closed position. A coiled spring 38 surrounds stem 36 and rests on the lower member 32 of the bracket 30. Its upper end engages the lower side of the projecting ends of a cross pin 39 extending transversely through and affixed in

the stem 36. This is a relatively strong spring and constantly urges the stem 36 toward its uppermost position in which the horizontal holding member 37 may engage the lower face of the manhole ledge or the lower face of the bracket member 32 where the cover is not on the manhole. In the position of Fig. 3, which, as will appear, is the locking or clamping position of the holder 37, the inner upwardly bent end 40 thereof stands flatly against the face of the bracket 30 and prevents turning of the lock arm 37 from its locking position. The spring 38 also accommodates any variation in thickness of the manhole ledge, such as may be taken care of by the slot adjustment of the clamps or holders 20 on the other side of the center of the cover.

In order to push the stem 36 of the lock down and to turn it a partial turn to free the locking arm 37 from beneath the manhole ledge so that the cover may be raised at that edge from its seat preparatory to removing it entirely from the manhole, a suitable key or handle 42, Fig. 3, is provided. This key is tubular and is adapted to be pushed down over the stem 36 of the clamp through the keyhole 35 in the cover plate and through the opening in the member 31 of the bracket 30. The lower end of the key is slightly bevelled, preferably as indicated, to aid in its ready engagement over the end of the stem and its passage downwardly over it, and is provided with opposed recesses 43 formed to engage over and receive the projecting ends of cross pin 39 in the stem 36. By this means the stem 36 of the lock may be pushed downwardly and turned to free the arm 37 from the manhole ledge so that the cover is free to be lifted from its seat at that edge, and then be withdrawn to free the clamps or holders from the manhole ring at the opposite edge of the cover, so that the cover may be completely removed. The cover may be applied to the manhole by the reverse operations of resting it edgewise at its rim between holders 20 on the ledge seat and tipping and lowering its opposite edge downwardly whereby to slide the holders 20 under the manhole ledge, and seating the cover in its peripheral seat. The key may then be pushed down and turned to swing the locking arm 37 out under the manhole ledge. When the key is released and withdrawn, the arm 37 is raised by the spring and engages the ledge as described, and the cover is held against unauthorized removal.

Further to safeguard the cover against being tampered with and to ensure its being locked in position, the key may be provided with a pin 44 rigidly secured thereto, which when the key is pushed downwardly passes through the slot portion 45 of the keyhole 35. When the key and stem are so pushed down to the dotted-line position of Fig. 3 and turned, the pin 44 engages under the cover and the key cannot then be withdrawn. At this time the upturned end 40 of the locking arm 37 is below the member 32 of the bracket 30 and can be turned. Ordinarily, to be sure the locking arm 37 clears the inside of the manhole ring, the key is turned to the mid-position, that is, 180°, which may be termed the unlocked position of the clamp. At this time the end of the pin 44 on the key 42 enters the horizontal slot 33 of the bracket 30 as the key is turned and then jumps up into the vertical notch 34 of said slot, on account of the upward thrust of the spring 38, assuming at this time the key is not being heavily pushed downwardly.

This prevents the key from being turned in the cover, and since it cannot be withdrawn from the cover and it and the parts associated therewith are of rugged and strong construction, the key makes a convenient handle for assisting in lifting the cover and handling and manipulating it in applying it to and removing it from the manhole. At this time also the upturned end 40 of the locking bar 37 has swung around and slides up along the squared end of the member 32 of bracket 30, so that the locking arm 37 itself is additionally locked in its off or unlocked position and cannot be turned.

With the key projecting up from the cover, the cover is not likely to be forgotten or left in that condition after putting it in place on the manhole; but in order to remove the key it must be pressed down and turned to the original position, where the pin 44 can be drawn out the slot 45 of the keyhole, and in so doing the clamping or locking bar 37 is turned to locking position, as in Fig. 3, and the cover is locked in place. Thus, the locking of the cover is not forgotten or the cover intentionally left unlocked and the key removed.

Again, should the key be removed while the cover is not on the manhole, the cover cannot be again seated in its place on the manhole, because in removing the key the locking bar 37 has been swung outwardly to its locking position and would prevent the seating of the cover. It is necessary in such case to reinsert the key in the cover and turn the arm 37 to its unlocked position before the cover can be reseated on the manhole.

Without further elaboration, the foregoing will so fully explain the gist of the invention that others may, by applying current knowledge, readily adapt the same for use under varying conditions of service, without eliminating certain features which may properly be said to constitute the essential items of novelty involved, which items are intended to be defined and secured by the following claims.

I claim:

1. A safety manhole cover for peripherally seating on the thick-walled ledge of a manhole and having locking devices on the underside of the plate for engaging under the ledge to resiliently lock the cover in its seat, one of said devices having a laterally extending locking member mounted to be turned outwardly into locking position under such an adjacent ledge or inwardly into unlocked position within the vertical limits of the ledge, the cover having a keyhole above the said member, a key for insertion in said hole for so turning said member into its locking or unlocking position, the key, hole and member being interrelated to prevent removal of the key from the cover when the said member is in other than its locking position, and spring-operated means to prevent turning of the key in the final unlocked position of the parts.

2. A safety manhole cover comprising a cover plate adapted to be peripherally seated on the thick-walled ledge of a manhole, locking devices on the underside of said plate having laterally and outwardly extending arms to resiliently engage under the surrounding ledge to lock the cover in place on its said seat, one of said devices having a vertical stem carrying at its lower end its said locking arm, the cover having a keyhole into which the upper end of said stem projects, a spring on the stem urging it upwardly, stop means to prevent rotation of the stem and locking arm when in locking position, and a key formed to fit into said keyhole to engage and grip the said stem and serving when manually pressed to depress the stem and its arm to free the said stop means and by rotation to turn the stem and arm into unlock position.

3. A safety manhole cover for thick-walled manholes including a locking device mounted on the underside of the cover, said device including a bracket, a vertical stem in said bracket having its upper end projecting into a keyhole formed in the cover and a laterally extending clamping member at its lower end to engage under the manhole ledge for clamping the cover in place on the manhole, a spring tensioned to lift said stem and member into clamping position, a projecting stop on said stem, and a key having a hollow shank adapted to be inserted in said hole over said stem and having engaging recesses in its end for said stem stop, the key operating to depress and rotate said stem to clamp and unclamp the same.

4. A safety manhole cover for thick-walled manholes including a locking device mounted on the underside of the cover, said device including a vertical stem having its upper end projecting into a keyhole formed in the cover and a laterally extending clamping member at its lower end to engage under the manhole ledge for clamping the cover in place on the manhole, locking means for said stem and member in both clamping and unclamping positions, a spring tensioned to lift said stem and member into clamping and locking position, a projecting stop on said stem, a key having a hollow shank adapted to be inserted in said hole over the said stem and having stem stop engaging recesses in its end, the key operating to depress and rotate said stem to lock and unlock and clamp and unclamp the same, the keyhole having a slot extension in definite relation to the locking position of the stem and clamping member, and a projection on the shank of the key passing through said slot when the key is inserted in the keyhole and depressed, said projection engaging under the cover when the key is so depressed and turned and thereby preventing the withdrawal of the key from the cover except 85 when the clamping member is in the clamping position.

5. A removable safety cover for a manhole in a thick-walled top slab of a subterranean catch basin or the like, comprising a cover plate having peripheral support on the top of the circumferential ledge of the manhole in the top slab, vertical brackets secured to the bottom of said plate and extending substantially below the same, and clamping arms mounted at the lower ends of said brackets and substantially spaced from said plate, said arms extending horizontally outward to resiliently engage under and hold to the lower side of said manhole ledge to clamp and hold the cover in place on the top of the slab and manhole, the said brackets at one side of the center of the plate having fixedly adjustable vertical legs, the horizontal clamping arms therefrom being resilient to enable them to be radially slipped under and off the ledge in hingedly applying the cover to the manhole and removing the same therefrom and exerting a clamping action on the ledge when the cover is seated thereon, a vertically reciprocating upwardly spring-pressed rotatable stem in the bracket on the other side of the center of the plate, the clamping arm of that bracket being rigidly secured to the lower end of said stem, stop means preventing rotation of said stem and arm in the raised clamping position, the cover plate having a keyhole, the upper end of said stem being accessible through said keyhole, and a separable key insertable through the keyhole and engageable with said stem and manually operable to depress and free the stem and arm from said stop means and to rotate the same between said positions.

6. A removable safety cover for a manhole in a thick-walled top slab of a subterranean catch basin or the like, comprising a cover plate having peripheral support on the top of the circumferential ledge of the manhole in the top slab, vertical brackets secured to the bottom of said plate and extending substantially below the same, and clamping arms mounted at the lower ends of said brackets and substantially spaced from said plate, said arms extending horizontally outward to resiliently engage under and hold to the lower side of said manhole ledge to clamp and hold the cover in place on the top of the slab and manhole, one of said brackets having a vertical portion corresponding to the thickness of the said ledge and with horizontally projecting bottom and intermediate portions having vertically aligned apertures therein, the cover having a keyhole in line with said apertures, a vertically movable and rotatable stem mounted in said apertures, the clamping arm of the said bracket being secured to the lower end of said stem beneath the said bottom portion of the bracket, a coiled spring on said stem urging it upwardly, interengaging parts on the arm and the said bottom portion in the clamping position of the arm and locking same against rotation, and a separable key insertable through said keyhole to grip the said stem to depress and unlock the arm and to rotate it.

7. A removable safety cover for a manhole in a thick-walled top slab of a subterranean catch basin or the like, comprising a cover plate having peripheral support on the top of the circumferential ledge of the manhole in the top slab, vertical brackets secured to the bottom of said plate and extending substantially below the same, and clamping arms mounted at the lower ends of said brackets and substantially spaced from said plate, said arms extending horizontally outward to resiliently engage under and hold to the lower side of said manhole ledge to clamp and hold the cover in place on the top of the slab and manhole, one of said brackets having a vertical portion corresponding to the thickness of said ledge and with horizontally projecting bottom and intermediate portions having vertically aligned apertures therein, the cover having a keyhole in line with said apertures, a vertically movable and rotatable stem mounted in said apertures, the clamping arm of said bracket being secured to the lower end of said stem beneath said bottom portion of the bracket, a coiled spring on said stem urging it upwardly, the clamping arm having an upstanding portion engaging said bracket in the raised clamping position of the arm to prevent rotation thereof, and a key insertable in the keyhole and temporarily engaging said stem manually to depress said stem and rotate the clamping arm.

8. A removable safety cover for a manhole in a thick-walled top slab of a subterranean catch basin or the like, comprising a cover plate having peripheral support on the

top of the circumferential ledge of the manhole in the top slab, vertical brackets secured to the bottom of said plate and extending substantially below the same, and clamping arms mounted at the lower ends of said brackets and substantially spaced from said plate, said arms extending horizontally outward to resiliently engage under and hold to the lower side of said manhole ledge to clamp and hold the cover in place on the top of the slab and manhole, one of said brackets having a vertical portion corresponding to the thickness of the ledge and with horizontally projecting bottom and intermediate portions having vertically aligned apertures therein, the cover having a keyhole in line with said apertures, a vertically movable and rotatable stem mounted in said apertures, the clamping arm of said bracket being secured to the lower end of said stem beneath the bottom portion of the bracket, a coiled spring on said stem urging it upwardly, interengaging parts on the arm and said bottom portion in the clamping position of the arm and locking same against rotation, and a separable key insertable through said keyhole to grip said stem to depress and unlock the arm and to rotate it, said key having a lateral projection engaging under the cover when depressed and turned to an unlocked position thus preventing its withdrawal, said plate having a recess into which said projection is raised by said spring when the key is turned to the final locked position.

9. A safety manhole cover to be secured to flanged manholes comprising a cover plate to peripherally engage such a manhole, circumferentially spaced resilient clamps secured to the underside of said plate to resiliently engage such a flange, the clamp on one side of the center of said plate having a rotatable stem resiliently urged toward said plate, a locking member engageable with such a flange fixed to said stem and rotatable therewith, and a separable key engageable with said stem to effect axial movement and rotation thereof, said plate having a key receiving aperture therein in axial alignment with said stem.

10. A safety manhole cover to be secured to flanged manholes comprising a cover plate having peripheral support to engage the flange of such a manhole, circumferentially spaced resilient adjustable clamps on the underside of said plate for engaging such a flange, the clamp on one side of the center of the cover having a rotatable stem resiliently urged toward said plate, a locking member fixed to the lower part of said stem and rotatable therewith, and a separable key engageable with said stem to effect axial movement and rotation thereof, said plate having an aperture therethrough in axial alignment with said stem whereby said key may be inserted through said aperture to rotate said stem to move said locking member between a disengaged position and a position whereby the locking member resiliently engages such a flange.

11. A safety manhole cover to be secured to flanged manholes comprising a cover plate to peripherally engage such a manhole, circumferentially spaced resilient clamps secured to the underside of said plate to resiliently engage such a flange, the clamp on one side of the center of said plate having a rotatable stem resiliently urged toward said plate, a locking member engageable with such a flange secured to said stem and rotatable therewith, a separable key engageable with said stem to effect axial movement and rotation thereof, said plate having a key receiving aperture therein in axial alignment with said stem, means to prevent removal of said key for all positions of said locking member other than the flange engaging position, and means to prevent rotation of said stem unless said stem is axially moved by said key.
